UNITED STATES PATENT OFFICE.

OTTO FISCHER AND WILHELM WALTHER, OF STUTTGART, GERMANY, ASSIGNORS TO
ROBERT BOSCH AKTIENGESELLSCHAFT, OF STUTTGART, GERMANY.

IGNITION COIL FOR COMBUSTION MOTORS.

Application filed April 12, 1928, Serial No. 101,478, and in Germany June 4, 1925.

This invention relates to ignition coils for combustion motors, especially that kind of ignition coils, which have an enclosed magnetic circuit and a removable protective casing. The purpose of the invention is to arrange the coil on that part of the vehicle, designated for this purpose, in such a manner, that the coil can be uncovered to gain access thereto by merely slipping or removing the casing or housing thereof from the coil without such removal being obstructed or hindered in any way by the transformer yoke.

This purpose is effected, according to the invention, by arranging the parts so that the winding is supported by the iron core of the ignition coil, such core being suspended from the casing holder, while the transformer yoke is secured to the coil casing.

In the accompanying drawing, in which one form of construction of our improved ignition coil is illustrated,

Fig. 1 shows a longitudinal section through an ignition coil, the wiring diagram being indicated by thin lines.

Fig. 2 is a side elevation and

Fig. 3 a plan view of the ignition coil and

Fig. 4 is a cross section on the line A—B of Fig. 1.

In the drawing our invention is shown in connection with an ignition device such as set forth and claimed in application No. 35,798, filed June 8, 1925, by Erich Klaiber, and which consists in an iron core *b* provided at its ends with enlargements or shoes *b'*, so as to be practically H-shaped as seen best in Fig. 4, the outer faces of the enlargements or shoes *b'* are on arcs of the same circle. The path for the magnetic lines of force issuing at the shoes is closed by an iron ring or yoke *h* concentric with the faces of the shoes *b'*, leaving an air-gap *h'* between the two shoes *b'*, on the one hand, and the ring or yoke *h*, on the other.

The winding *a* of the ignition coil is arranged on a core *b*, which is supported by bolts *c*, which on the one hand engage with the ends or shoes *b'* of the core *b*, projecting from the winding *a* and on the other hand are secured to a holder *d*, which constitutes a cover for the casing *g* described below. The latter is provided with an extension *e*, which serves for securing the ignition

coil to the motor and for this purpose has holes *f* for the fastening screws. The coil 55 is enclosed by a casing *g*, which is held in position by screws *k*, engaging with the extended nut threads of the bolts *c*.

The ring or yoke *h*, which is formed of laminated iron, is flanged or seated in the 60 casing *g* by first making the upper part of the said casing of the same diameter as that of the middle portion *i*, then slipping the ring or yoke down into the upper enlarged portion until it rests on the lower shoulder 65 thereof, and thereupon spinning or drawing the upper portion of the casing above the ring by suitable and well known tools and appliances so as to contract the same above the ring and thus hold the same in place, 70 without requiring any further fastening means.

On the holder *d* a binding screw *m* for attaching the interrupter to the one end of the primary winding is secured, while the other 75 end of said primary winding is attached to a binding screw *n*. To the latter is connected also one end of the starting resistance *o* for the primary coil, while the other end of said resistance is connected to a binding screw *r*, 80 to which also the source of current is connected. One end of the secondary winding is connected to the primary winding while its other end is connected with a contact *p*, which is in engagement with a binding screw 85 or stud *q* on the bottom of the casing.

As it may be seen from the drawing, the coil and its connections may be inspected and examined after the removal of the casing, without the examining person being impeded 90 by the iron yoke. Nevertheless the coil can be made again operative by simply replacing the casing in its position.

The iron yoke *h* can be fastened in the casing instead of edging the yoke into the 95 casing also by indentations of the casing above and below said yoke, said indentations serving to hold the yoke in position.

Obviously the holder or cover *d* of the coil may be fastened to the motor also in any 100 other known manner, for instance it can be made approximately round and can be held on the motor by a spring tape.

We claim:

1. An ignition device for combustion 105 motors, comprising in combination a removable

protective casing, an iron yoke secured to said casing, a cover for the casing, an iron core, supported by said cover and adapted to receive the winding of the ignition coil, said casing and yoke being of such interior dimensions as to clear the other parts of the ignition device, whereby, after the removal of the same, an inspection and examination of the coil can be made without being impeded by the iron yoke.

2. An ignition device for combustion motors, comprising in combination a removable protective casing, an iron yoke secured to said casing by a recess in the wall of said casing, a cover for said casing, an iron core, supported by said cover and adapted to receive the winding of the ignition coil, said casing and yoke being of such interior dimensions as to clear the other parts of the ignition device, whereby, after the removal of the same, an inspection and examination

of the coil can be made without being impeded by the iron yoke.

3. An ignition device for combustion motors, comprising in combination a removable protective casing, an iron yoke secured to said casing by means seated in the wall of said casing, a cover for the casing for securing the coil to the motor, an iron core, supported by said cover and adapted to receive the winding of the ignition coil, said casing and yoke being of such interior dimensions as to clear the other parts of the ignition device, whereby, after the removal of the same, an inspection and examination of the coil can be made without being impeded by the iron jacket.

In testimony whereof we have hereunto affixed our signatures.

OTTO FISCHER.
WILHELM WALTHER.
